UNITED STATES PATENT OFFICE.

HARRY F. ROACH, OF ST. LOUIS, MISSOURI, ASSIGNOR TO REINFORCED RAIL JOINT COMPANY, OF ST. LOUIS, MISSOURI, A CORPORATION OF MISSOURI.

METHOD AND APPARATUS FOR MAKING RAIL-JOINT MEMBERS.

Application filed September 27, 1924. Serial No. 740,264.

This invention relates to the manufacture of rail joints of the type commercially known as "Roach" joints, wherein the two members of the joint each consist of a bar 5 arranged at one side of the abutting rails and provided intermediate its ends with rail engaging portions that bear against the undersides of the heads of the rails and against the upper sides of the base flanges of 10 the rails, the end portions of said bar being reduced in height and spaced away from the heads and base flanges of the rails so as to permit the rails to deflect slightly and also move upwardly at the ends of the joint 15 under load.

The "Roach" joint above referred to has gone into extensive commercial use and has effected a considerable saving in the cost of maintaining railway tracks. Accordingly, 20 it has become necessary to devise a method of manufacture that will enable "Roach" joints or "Roach" bars to be manufactured economically on a commercial scale and at the same time reduce to a minimum 25 the objectionable characteristics and unsatisfactory features of conventional methods used in the manufacture of rail joints.

It is well known to those skilled in the art that any constant section produced by 30 rolling is only approximately constant, due to the excessive wear of the rolls which permits the section to increase or decrease in dimensions, depending upon the character or design of the element rolled. In a general 35 way rail joints are more or less difficult to roll, because they are subject to all of the drawbacks of the rail section and to many others in addition, due to their irregular section and lack of symmetry. In the common splice bar, for example, the angles at 40 which the section is rolled are limited by danger of undercuts and the shape of the passes in which the piece is necessarily reduced are favorable to the formation of laps and seams. The section of the "Roach" 45 joint member or "Roach" bar comes under the class of "plate or bar section" and not under the class of "irregular section". The "plate section" is not subject to all the difficulties in manufacture of rolling that "irregular sections" are subject to, but the "plate section" is subject to a condition produced by the rapid wearing of the rolls.

As it is a matter of common knowledge to those skilled in the art that the fish of 55 the rail varies in dimensions from the beginning to the end of a day's roll, by decreasing in dimension, while the fish of the joints vary in dimension from the beginning to the end of a day's roll, by increasing in dimension, 60 the assembling in the track of these elements manufactured with varying dimensions not only occasions inconvenience, but militates towards the increase of maintenance of the track. Accordingly, it becomes desirable to 65 reduce this variation to a minimum in the joint, which means the introduction of a subsequent operation, such as a die forged or pressed method.

All rolled joints are subject to the operation of punching after rolling. The "Roach" joint being of a "plate section" lends itself to the introduction of a shearing and forging method coincident with the punching operation; accordingly, a "Roach" bar may 70 be produced with no more handling or operations than the ordinary rolled joint with the intermediate or central portion of the bar pressed or forged to almost an exact theoretical fish distance. Furthermore, as 75 is well known to those skilled in the art, a die process of pressing and forging produces a fineness of surface and dimension that cannot be produced in rolling. It also materially benefits the material of which 80 the bar or joint member is constructed.

A "Roach" joint member or "Roach" bar may be made in accordance with my present invention from a bar having approximate constant section of most any reasonable plate 90 shape such as Merchant bar, or it may be made from a bar of approximately constant section, which section is that of the intermediate portion of the conventional "Roach" joint; the use of the latter section occasions 95 no more wear on the rolls, but much less work on the dies.

My preferred method consists of shearing the intermediate portion and the end portions of the bar from which the joint member is being formed, and then pressing or forging said sheared edges so as to produce a rail joint member that has the distinguishing characteristics of the "Roach" rail joint, to wit, beveled surfaces on the intermediate 105 portion of the member that bear against the

undersides of the heads and against the upper sides of the base flanges of the rails, and reduced end portions that are spaced away from said heads and flanges. An alternative method consists in simply shearing off and forging the end portions of a rolled bar which is of such cross section that the intermediate portion or unsheared portion of the bar will correspond to the intermediate portion of a "Roach" rail joint member, and still another method consists in taking a bar of the approximate cross section of the finished joint member, shearing and forging the intermediate portion of the bar and then simply shearing off but not forging the end portions of the bar so as to reduce the height or depth of said end portions.

The main object of my invention is to simplify the manufacture of "Roach" rail joint members or "Roach" bars.

Another object is to produce a "Roach" bar or rail joint member whose reduced end portions have beveled edges inclined at substantially the same angle as the edges of the intermediate portion of the member which contact with the heads and the base flanges of the rails.

To this end I have devised a method of manufacturing a rail joint member of the general type referred to, which, briefly stated, is characterized by arranging a bar or substantially oblong shaped member in a press, punching bolt holes in said member, shearing off the upper and lower edges of a certain portion or portions of said member and beveling said sheared edges in a single operation, the beveling of said sheared edges being effected by forging the metal in said member.

The apparatus that is used to punch, shear and forge the bar from which the rail joint member is formed can be constructed in various ways without departing from the spirit of my invention, but I prefer to equip said apparatus with a combined shearing and forging die whose female member is provided with cutting surfaces and pressing surfaces arranged so that said cutting surfaces shear off the longitudinal edges of the intermediate portion and end portions of the bar, and said pressing surfaces thereafter forge the sheared edges of said bar in such a way as to produce a joint member provided with a beveled edge intermediate portion and beveled edge reduced end portions. Short pieces of bar of the proper length can be fed into the press, one after the other, or a long bar can be fed into the press and severed into short lengths simultaneously with the operation of punching, shearing and forging the bar so as to convert it into a finished rail joint member.

Figure 1 of the drawings is a side elevational view of a rolled bar that I prefer to

use in manufacturing rail joints in accordance with my present invention.

Figure 2 is a cross-sectional view of said bar.

Figure 3 is a view partly in front elevation and partly in vertical transverse section of one form of apparatus that can be used in practicing my method.

Figure 4 is a view partly in side elevation and partly in longitudinal section of said apparatus.

Figure 5 is a fragmentary view, the left hand half of which is taken on the line 5—5 of Figure 4, looking downwardly, and the right hand half of which is taken on the same line looking upwardly.

Figure 6 is a side elevational view of the rail joint member produced by my method; and

Figure 7 is an end view of said rail joint member.

In the drawings A designates a rolled bar that is preferably provided with oppositely-inclined or oppositely-beveled, longitudinal edges *a*, as shown in Figure 2. In manufacturing the joint member the bar A is preferably sheared and forged by cutters and pressing surfaces that act on the intermediate portion of the bar and on the end portions of the bar in such a way as to produce a rail joint member of the kind shown in Figures 6 and 7 that has an intermediate portion provided with oppositely-beveled top and bottom edges *a* that bear against the undersides of the heads of the rails and against the upper sides of the base flanges of the rails, and reduced end portions of less depth or height than said intermediate portion that have beveled edges *b* inclined transversely and of approximately the same angle as the beveled edges *a* of the intermediate portion. The cutters that act on the end portions of the bar are arranged at a slight angle with relation to the longitudinal axis of the bar so that they will shear the longitudinal edges of the end portions of the bar along the lines *c* of Figure 1, and thus produce a member whose end portions diminish gradually in height or depth from the intermediate portion towards the end of said member.

The cutters which act on the intermediate portion of the bar are disposed parallel with relation to the longitudinal axis of the bar so as to produce a member whose intermediate portion has straight edges, as distinguished from the longitudinally inclined edges on the end portions of said member. The pressing surfaces, previously mentioned, that forge the sheared edges of the bar, are so disposed that the metal in the intermediate and end portions of the bar will be subjected to pressure in a direction to produce oppositely-inclined, beveled edges *a* on the intermediate portion

of the bar and oppositely-inclined, beveled edges *b* on the end portions of the bar. During the operation of shearing and forging the intermediate and end portions of the 5 bar, bolt holes *d* are formed in the bar to receive the bolts that are used to hold the two members of the joint in engagement with the abutting rails which said joint members embrace. Such a method enables 10 a "Roach" bar or rail joint member to be made at a very low cost, and it also produces a joint member in which the reduced end portions of the member have forged top and bottom edges that are beveled at substantially 15 the same angle as the beveled rail engaging surfaces *a* on the intermediate portion of the member that contact with the heads and base flanges of the rails.

The apparatus that I prefer to use in practicing 20 my method comprises a combined shearing and forging die composed of a stationary male die member 1 and a co-operating movable female die member 2. Said apparatus also comprises punches 3 combined 25 with the female die member 2 in such a way that they can move relatively to said member to form bolt holes in the bar being operated on, and if desired, spring-pressed work-clamping members 4 can be associated 30 with the punches 3 so as to facilitate the withdrawal of said punches from the bar during the upward movement of the platen or reciprocating element of the press. The 35 bar A that I prefer to use is preferably of such cross-sectional shape that when it is positioned upon or fed onto the stationary male member 1 of the die, it will rest squarely upon and be firmly supported by said member during the punching, shearing and 40 forging operations. Thus, as shown in Figures 2 and 3, the bar A is provided on its underside with a flat central surface, and the male member 1 of the die is provided in its top face with a cavity for receiving the 45 central portion of the bar and two raised surfaces 1^a, flat or of other desired shape, at the opposite sides of said cavity that are engaged by the surfaces adjacent the edges of the bar when the bar is positioned on said 50 die member. The male member 1 of the die is carried by a stationary member B and the female member 2 is carried by a reciprocating member C that is arranged inside of a reciprocating member D which is connected 55 to the platen or other reciprocating element of the press. The member C is held in longitudinal alignment with the member B by suitable guides, and springs 5 are interposed between the members B and C so as 60 to separate the die members 1 and 2 at the completion of the forging operation, said springs 5 surrounding rods 6 that project upwardly from the member B through the member C and which are provided at their 65 upper ends with adjustable stops 7 that limit

the upward movement of the die carrying member C. The stationary supporting structure on which the member B rests prevents the rods 6 from moving downwardly relatively to said member B, and upward movement of said rods relatively to the member B is prevented by heads or abutments 7^a at the lower ends of said rods that fit in recesses on the underside of the member B.

The punches 3 are rigidly mounted in the 75 member D and project downwardly from same through the member C and through the tubular work holding devices 4 that surround the punches. Each of said work holding devices 4 is backed up by a coiled expansion spring 8 that is arranged in a pocket or recess in the member C, the tension of said springs 8 being such that when the member D is in its raised or elevated position, the work holding devices 4 will be maintained in 80 the position shown in Figure 4, wherein it will be noted that they project beyond the ends of the punches 3. At such times, namely, when the platen of the press is raised, the member D that carries the punches will be 85 held spaced away from the upper end of the die carrying member C. If desired, means can be provided for cooling the punches so as to prevent them from becoming overheated when the bar from which the joint 90 member is formed is punched, sheared and forged in a heated condition, the means herein illustrated for this purpose consisting of water circulating pipes 9 in the punch carrying member D that communicate with ducts 100 or circulating tubes in the punches 3.

The female member 2 of the die has a longitudinally-disposed cavity provided at its intermediate portion and at its end portions with cutting surfaces and pressing surfaces 105 arranged so as to shear off the longitudinal edges of the intermediate portion and end portions of the bar and then forge said sheared edges so as to bevel the same. In the die member herein illustrated two sets 110 of cutting edges 10 and 11 are provided, one of said sets being arranged in advance of the other, so that said advanced set will shear off the longitudinal edges of the intermediate and end portions of the bar and the other set will thereafter remove any rough or uneven surfaces on the sheared edges produced by displacement of the metal resulting from the passage of the punches through the bar, or from any other causes. The 115 pressing surfaces with which the die members are equipped are designated in the drawing by the reference character 12, said pressing surfaces consisting of flat, oppositely-inclined faces, as shown in Figure 3, that extend longitudinally of the die member 2 and which slope inwardly towards the longitudinal axis of said die member. The cutting edges 10 and 11 and pressing surfaces 120 that act on the end portions of the bar are 125 130

inclined slightly with relation to the longitudinal axis of the die member 2, as shown in Figure 5, and the cutting edges and pressing surfaces that act on the intermediate portion of the bar extend parallel to the longitudinal axis of the die member 2. The male member 1 of the die is of course provided with holes 3^a that co-operate with the punches 3 to shear the metal engaged by the lower ends of said punches during the downward movement of the platen, and in the apparatus herein illustrated the bottom face of the cavity in the upper end of the stationary die member 1 is provided with longitudinally-disposed channels 13 that form a clearance for raised letters which are formed on the underside of the bar A during the operation of rolling same, said channels 13 also forming a relief for the flow of the metal during the operation of converting the bar into a rail joint member. If the joint members are formed from a long bar that is severed into short lengths during the operation of punching the bolt holes and shaping the intermediate and end portions of the joint member, the punch carrying member D of the apparatus will be equipped with shearing devices 14 that extend transversely across the ends of the female die member 2 and which co-operate with the same to shear a long bar that rests upon the stationary member 1 of the die.

In practicing my method the bar A from which the joint member is to be formed is positioned upon the male member 1 of the die, as shown in Figure 3. Thereafter, the platen of the press is moved downwardly so as to cause the punches 3 to form bolt holes in the bar and cause the cutting edges 10 and 11 and the pressing faces 12 to shear off the longitudinal edges of the intermediate portion and the end portions of the bar and bevel said sheared edges by the pressure exerted on same by the pressing faces 12. Any rough edges that are left by the cutters 10 or any rough or uneven surfaces that are produced by the displacement of the metal when the punches pass through the bar are trimmed off by the cutters 11, thus insuring the sheared edges of the bar being smooth and even when the inclined pressing faces 12 act on said sheared edges. During the first portion of the upward movement of the platen the work-clamping members 4 remain in engagement with the bar while the punches are moving upwardly out of the bar, due, of course to the pressure exerted on said work-clamping members by the springs 8 that back up said members the female member 2 of the die being restored to its elevated position by the expansive force of the springs 5 that are interposed between the members B and C of the apparatus.

The above described method of producing a rail joint member of the so-called "Roach"

type enables such rail joint members to be manufactured cheaply; it produces a high character product and it produces a rail joint member whose reduced end portions have beveled edges that are disposed at substantially the same angle as the surfaces on the intermediate portion of the member that bear against the undersides of the heads of the rails and against the upper sides of the base flanges of the rails.

Having thus described my invention, what I claim as new and desire to secure by Letters Patent is:

1. An apparatus for making a rail joint member of the kind that comprises a portion which bears against the heads and base flanges of the rails and portions that are spaced away from said heads and flanges, consisting of a male die member, a co-operating female die member provided with cutting surfaces for shearing off the longitudinal edge portions of a bar positioned between said members, and pressing surfaces on said female die member for beveling said sheared edges.

2. An apparatus for making a rail joint member of the kind that comprises an intermediate portion which bears against the heads and base flanges of the rails and reduced end portions that are spaced away from said heads and flanges, consisting of a male die member adapted to have a bar positioned on same, a co-operating female die member provided with cutting surfaces for shearing off the longitudinal edges of the end portions of said bar, pressing surfaces on said female die member for beveling said sheared edges, and punches for forming bolt holes in the bar.

3. An apparatus for making a rail joint member of the kind that comprises an intermediate portion which bears against the heads and base flanges of the rails and reduced end portions that are spaced away from said heads and flanges, consisting of a male die member adapted to have a bar positioned on same, a co-operating female die member provided with cutting surfaces and pressing surfaces for shearing and beveling the edges of the intermediate portion of said bar, independent cutting surfaces for shearing off the longitudinal edges of the end portions of said bar to reduce the depth or height of same, and punches for forming bolt holes in the bar.

4. An apparatus for making a rail joint member of the kind that comprises an intermediate portion which bears against the heads and base flanges of the rails and reduced end portions that are spaced away from said heads and flanges, consisting of a male die member adapted to have a bar positioned on same, a co-operating female member, cutting surfaces and pressing surfaces on said female member for shearing

- the longitudinal edges of the intermediate portion and end portions of said bar and beveling said sheared edges, and punches for forming bolt holes in the bar.
5. An apparatus for making a rail joint member of the kind that comprises an intermediate portion which bears against the heads and base flanges of the rails and reduced end portions that are spaced away from said heads and flanges, consisting of a male die member adapted to support a bar that is provided with oppositely-beveled, longitudinal edges, a co-operating female die member provided with cutting surfaces and pressing surfaces disposed so that portions of the longitudinal edges of said bar will be sheared off and said sheared edges thereafter beveled when said die members are brought together, and means for punching bolt holes in the bar simultaneously with the shearing and pressing operation.
6. An apparatus for making a rail joint member of the kind that comprises an intermediate portion which bears against the heads and base flanges of the rails and reduced end portions that are spaced away from said heads and flanges, consisting of a male die member that is adapted to support a bar, a co-operating female die member having a cavity for receiving said bar when said die members are brought together, cutters on said female die member for shearing off portions of the longitudinal edges of said bar, oppositely-inclined pressing faces on said female die member for forging the metal in said sheared edges so as to bevel the same, and punches for forming bolt holes in the bar while it is positioned between said die members.
40. 7. An apparatus for making a rail joint member of the kind that comprises an intermediate portion which bears against the heads and base flanges of the rails and reduced end portions that are spaced away from said heads and flanges, consisting of a male die member that is adapted to support a bar of substantially constant cross section that is provided with oppositely-beveled, longitudinal edges, a co-operating female die member provided with a cavity, cutting surfaces on the intermediate portion and end portions of said cavity for shearing off the longitudinal edges of the bar, inclined pressing faces adjacent said cutting surfaces for beveling the sheared edges of the bar, and means for forming bolt holes in the bar.
8. An apparatus for making a rail joint member of the kind that comprises an intermediate portion which bears against the heads and base flanges of the rails and reduced end portions that are spaced away from said heads and flanges, consisting of a male die member that is adapted to support a rolled bar provided with oppositely-inclined, beveled edges, a co-operating female die member provided with a cavity for receiving said bar and equipped with cutting surfaces for shearing off the longitudinal edges of the bar, inclined surfaces for forging said sheared edges, punches associated with said female die member for forming bolt holes in the bar, and spring-pressed, tubular work-clamping members surrounding said punches.
9. An apparatus for making a rail joint member of the kind that comprises an intermediate portion which bears against the heads and base flanges of the rails and reduced end portions that are spaced away from said heads and flanges, consisting of a stationary male die member provided with a top face of irregular contour that is adapted to receive a rolled bar, a co-operating female die member provided with cutting surfaces and pressing surfaces arranged so as to shear off the longitudinal edges of the intermediate portion and end portions of said bar and thereafter bevel the sheared edges, a movable member that carries said female die member, springs that act on said movable die carrying member and normally exert pressure on same in a direction to hold said female die member raised, a reciprocating element, rigid punches on said element that project downwardly through said female die member, tubular work-clamping members surrounding said punches and reciprocatingly mounted in said female die member, and springs that normally exert pressure on said work-clamping members in a direction tending to hold them projected beyond the ends of said punches.

HARRY F. ROACH.
